ABSTRACT

[51] Int. Cl.² E01B 29/10
[52] U.S. Cl. 104/9; 37/104;

New railroad crossties are placed on the rails of a railroad track and pushed along the track by a rail mounted vehicle. When the new crosstie is positioned over a crosstie in the railroad bed that is to be replaced, the ballast at one end of the old crosstie is removed, the rails are urged upwardly to relieve the force on the old crosstie, the new crosstie is then grasped and moved along its length laterally across the track until its trailing end clears the exposed end of the old crosstie, then the new crosstie is lowered and pushed against the exposed end of the old crosstie until the new crosstie pushes the old crosstie out from beneath the rails. A work head assembly is mounted at one end of the vehicle and includes a shovel and clamp assembly, and the work head assembly is movable laterally with respect to the rails of the railroad track to clear the soil away from the ends of the old crossties and to grasp and insert the new crossties beneath the rails.

RAILROAD CROSSTIE REPLACEMENT MACHINE

BACKGROUND OF THE INVENTION

When the crossties of a railroad are to be replaced, selected ones of the crossties are individually replaced without removing the rails from the railroad. Usually, the tie plates that hold the rails on the crossties are removed from an old crosstie, the rails urged in an upward direction to relieve the downward force on the old crosstie, and then the old crosstie is pushed or pulled laterally from beneath the rails. A new replacement crosstie can then be inserted in the space vacated by the old removed crosstie.

As illustrated in my U.S. Pat. No. 3,537,400, rail mounted vehicles have been developed for removing old crossties from railroad beds. The vehicle has a crosstie kicker on one of its sides which functions to urge or "kick" a crosstie laterally beneath the tracks, while at the other side of the vehicle a clamp mechanism grasps the protruding end of a partially removed crosstie and pulls the crosstie on out from beneath the rails.

While the prior art illustrates various means for ejecting old crossties from railroad beds, there is still a need for effective equipment that will not only eject old crossties from a railroad bed but will also expediently insert new crossties in the space vacated by an old crosstie.

SUMMARY OF THE INVENTION

Briefly described, the present invention comprises a crosstie replacement system for removing old crossties and inserting new crossties in a railroad. New or replacement crossties are distributed on top of the rails of a railroad track at locations where old crossties are to be removed. A railroad track mounted vehicle then moves along the track and pushes a new crosstie along the track until it is placed over and parallel to a crosstie that is to be removed from the bed. The rails are grasped by rail dogs suspended from the vehicle and the front end of the vehicle is raised by jacks carried on the vehicle to urge the rails upwardly away from the crossties and to relieve the downward force from the rails against the old crosstie. A work head on one side of the vehicle includes a shovel and a clamp assembly, and the shovel assembly functions to clear the soil or ballast away from one end of the old crosstie. The new crosstie is then grasped by the clamp assembly, moved along its length laterally with respect to the rails of the railroad track until its trailing end clears the exposed end of the old crosstie, the new crosstie is then lowered until it is at the level of the old crosstie, and then the new crosstie is forced back beneath the rails so that it pushes the old crosstie out from beneath the rails and occupies the space vacated by the old crosstie.

The clamp assembly and shovel are mounted on a housing at the front of the vehicle and a crosstie pusher or "kicker" is mounted in the other end of the housing. The crosstie kicker functions to push the crossties along their lengths laterally with respect to the rails of the track as the machine is manipulated in the crosstie replacement steps. The vehicle includes means for turning the support housing around so as to reverse the positions of the crosstie kicker with respect to the shovel and clamp assemblies, so that the crossties can be ejected and inserted in either direction.

Thus, it is an object of this invention to provide a crosstie replacement system which functions to both eject old crossties and insert new crossties in a railroad bed.

Another object of this invention is to provide apparatus for expediently and economically replacing crossties in a railroad bed.

Another object of this invention is to provide a method of replacing old crossties with new crossties in a railroad bed, which includes the step of pushing with a new crosstie against the old crosstie in a railroad bed to simultaneously force the old crosstie out from beneath the rails while inserting a new crosstie beneath the rails.

Other objects, features and advantages of the invention will become apparent upon reading the following specification, when taken in conjunction with the accompanying drawing.

BRIEF DESCRIPTION OF THE DRAWINGS

FIG. 1 is a side elevational view of a crosstie replacement vehicle which is in the form of a vehicle movable along the rails of a conventional railroad track.

FIG. 2 is a front elevational view of the crosstie replacement vehicle, with parts shown in cross-section and parts removed for clarity.

FIG. 3 is an end view of the work head assembly of the vehicle.

FIG. 4 is a top cross-sectional view, taken along line 30 4-4 of FIG. 3.

FIG. 5 is a schematic illustration of the hydraulic controls of the crosstie replacement vehicle.

FIGS. 6-11 are progressive schematic illustrations of the procedure for replacing a crosstie in a railroad track.

FIGS. 12 and 13 are progressive schematic illustrations of a method of removing a crosstie from a railroad track.

DETAILED DESCRIPTION

Referring now in more detail to the drawing, in which like numerals indicate like parts throughout the several views, FIG. 1 illustrates the crosstie replacement vehicle 10 which includes a base framework 11 mounted on railroad wheels 12. Diesel engine 13 is located over the rear wheels of the vehicle, and the engine 13 operates pump assembly 14. The liquid from pump assembly 14 is used to power the various components of the vehicle and to drive the vehicle along the railroad track 15. The several storage tanks for storing the hydraulic liquid and diesel fuel, the hydraulic conduits, counterweights and other conventional components of a system of this type are not illustrated in the drawings.

Upwardly extending framework 16 is mounted on the base framework 11 and includes a pair of upright supports 18 mounted at each side of the base framework 11 behind the forward wheels 12a of the vehicle, a second pair of upright support elements 19 mounted at the forward end of the vehicle in front of the forward wheels 12a, horizontal brace 20 and inclined brace 21 connected between the upright pairs of supports 18 and 19. Pairs of parallel arms 21 and 22 are each connected at one of their ends to the pairs of upright supports 18. The pairs of parallel support arms 21 and 22 are connected at their other ends to housing 24. A pair of lifting links 25 are connected at their lower ends to the lower pair of parallel support arms 21 and at their upper ends

to pivoting links 26. Pivoting links 26 are pivotally connected to framework support blocks 28. A pair of hydraulic rams 29 each have their cylinders 30 connected to the upstanding framework 16, and their ramrods 31 are connected to the pivoting links 26. With this arrangement, the movement of the ramrod 31 of the ram 29 lifts and lowers the pairs of parallel support arms 21 and 22 and the housing 24 at the front of the vehicle, and the parallel linkage of the pairs of parallel support arms 21 and 22 will maintain the housing 24 in the attitude illustrated.

A work head assembly 32 is mounted on one end of housing 24 and a crosstie kicker assembly 35 is mounted on the other end of the housing 24. Both the work head assembly and crosstie kicker assembly require fluid pressure for actuating their respective components, and a plurality of fluid conduits 36 communicate with the work head and with the housing 24. Since the work head 32 is movable (described in more detail hereinafter), the conduits 36 must be movable with the work head. Boom 38 is pivotally mounted at its end 39 to the upper portion of the upstanding framework 16 and projects forwardly over the upper portion of the vehicle, and turns downwardly at 40 in front of the vehicle, then forwardly again at 41 and then downwardly again at 42. The plurality of fluid conduits 36 extend through boom 38. Crossbar 44 is connected at one of its ends to the lower end of boom 38 and at the other of its ends to work head assembly 32. The plurality of fluid conduits 36 are supported by crossbar 44 as they extend from the lower end of boom 38 to the work head 32 and function to move the liquids from pumps 14 to the various rams on the work head assembly.

A pair of hydraulic jack assemblies 45 are mounted on the base framework 11 of the vehicle, with each jack assembly 45 being mounted on opposite sides of the vehicle and at the front wheels 12a of the vehicle. Jack assemblies include upstanding tubular guides 46 and 47 which are rigidly connected to the base framework 11, cross head 48 rigidly connected at its ends to the upper ends of the tubular guides 46 and 47, hydraulic ram 49 which has its cylinder 50 connected at its base to crossbar 48 and a distendable ramrod 51. Support foot 52 has upwardly extending guide bars 53 and 54 received in the guide tubes 46 and 47, and the ramrod 51 of the ram 49 is connected to the support foot between its guide bars 53 and 54. Thus, when ram 49 is distended or retracted, the support foot 52 will move down into engagement with the bed of the railroad track or upwardly to a retracted, travel position.

Rail dog assemblies 55 are mounted on the base framework 11. A pair of rail dog assemblies 55 are mounted on each side of the framework, with one rail dog assembly positioned in front of the one of the forward wheels 12a and the other rail dog assembly positioned behind the forward wheel. Each rail dog assembly includes a hinge connection to the base framework 11, and the hinge pin 57 allows the rail dog to pivot upwardly away from the railroad as illustrated, or downwardly toward engagement with the rails of the railroad. The rail dog assemblies 55 include a pair of clamp elements 58 and 59 which are pivotally connected together with pivot pin 60, which forms downwardly projecting jaws for grasping the ball of a rail. The jaws are shaped (not shown) so that when moved together they form a recess suitable for grasping the ball of a rail. The upper ends of the jaws 58 and 59 are movable toward and away from each other by means of

ram 61. Support chain 62 is connected at one of its ends to eye 63 and is connectable to the base framework 11 by inserting one of the chain links over the protrusion such as a bolt. Thus, chain 62 functions to hold the rail dog assemblies 55 up away from the rails when the vehicle is to travel along the railroad track.

Turntable assembly 65 is centrally mounted on the base framework 11 and includes a turntable 66, turntable stem 67, and hydraulic ram 68. The ram 68 causes the turntable 66 to move toward and away from engagement with the railroad bed between the rails of the railroad track, and the turntable 66 is rotatably supported on the framework 11. When the turntable 66 is forced in a downward direction against the bed of the railroad track it lifts the entire vehicle in an upward direction away from the railroad track, and the vehicle can then be turned around to face in the opposite direction.

A pair of side cranes 70 are mounted on the vehicle at opposite sides thereof in the vicinity of the front wheels of the vehicle. Each side crane 70 includes a support sleeve 71 mounted on the exterior surface of the jack guide tube 46 of the jack assembly 45, and upstanding pivotal mast 72 and a laterally extending boom 73. Brace 74 extends between the mast and the boom for support. The boom 73 is fabricated from an eye beam, and the upper and lower flanges 75 and 76 form a track for a boom trolley assembly 77. Winch 78 is suspended from the trolley assembly, and includes a winch housing 79, reel 80, electric motor 81, cable 82 and hook or other connection element 83 at the end of the cable 82. The crane 70 can be pivoted in its tubular support 71 so that its boom 73 projects out to the side or forwardly with respect to the vehicle, and the winch 78 moved along the length of the boom between the inner and outer stops 84 and 85.

Housing 24 at the front of vehicle 10 includes front wall 86, rear wall 89, and inner walls 90 and 91. A plurality of forward and rearward wedge plates 92 and 93 extend downwardly from housing 24 and include beveled wedge surfaces 92a and 93a. A pair of push bars 94 are mounted on housing 24 and each push bar 94 extends across a rail of the railroad track. Each push bar includes a push bar support stem which extends upwardly from push bar 94, and the stem is telescopically received in a stem housing 96. The stem housings 96 are rigidly connected to the rear wall 89 of the housing 24, and a stop pin 97 extends through the upper end of the stem 95 to keep the push bars from falling out of the sleeves 96.

A pair of inwardly facing channel bars 100 and 101 are connected to the inner surfaces of housing 24 at the lower portion of the housing and extend horizontally across the housing. The channels 100 and 101 form a raceway for trolley 102. Hydraulic ram 103 is supported in the raceway and moves the trolley 102 along the raceway. The kicker assembly 35 is supported at the end of trolley 102 and includes a downwardly extending support 106 connected to the trolley and kicker feet 107 and 108 each pivotally connected at their upper ends to the downwardly extending support 106. Eyes 109 and 110 are connected to the kicker feet 107, and chains 111 and 112 are each connected at one of their ends to an eye 109 and 110 and to a protrusion such as bolts 113 and 114 extending from the front and rear walls 88 and 89 of the housing 24. As illustrated in the dashed lines at the lower portion of the housing 24 in FIG. 1, the kicker feet can be spread apart by applying tension to the

chains 111 and 112, so that the kicker feet are retracted upwardly and therefore out of the way of a crosstie.

As shown in FIG. 1, a pair of guide tubes 116 and 117 are mounted on each upper support arm 22 of the pairs of parallel support arms, and a bar 118 is slidably received in tubes 116 and 117. The bar can be maintained in the position illustrated in FIG. 1 by the insertion of a connector pin 119 through aligned openings in tubes 116 and the bars 118, or the bars 118 can be distended through the tubes 116 and 117 until a stop pin 120 engages the rear portion of tubes 117. A crossbar 121 is connected to the outer ends of bars 118, and an eye 122 is connected to the lower portion of crossbar 121. Chain 123 is connected to eye 122, and a similar eye 124 is connected to the upper portion of housing 24. When it is desired to reverse the work head assembly 32 with the crosstie kicker assembly 105, the housing 24 is lowered so that it rests on the rails of the railroad track and the pins 125 and 126 that connect the housing 24 to the pairs of parallel support arms 21 and 22 are removed to disconnect the housing from the vehicle. The connecting pins 119 which extend through tubes 116 and bars 118 are removed so that the bars 118 will slide forwardly with respect to the vehicle. The hydraulic conduits 36 and the crossbar 44 are disconnected from the work head, and the vehicle is then backed away from the housing 24. The bar 118 will slide through the tubes 116 so that the chain 123 will not pull the housing over. When the vehicle is displaced away from the housing 24, the pairs of parallel support arms 21 and 22 are lifted by the ram 29, so that the crossbar 121 and chain 123 lift housing 24 away from the track. A workman can then easily rotate the housing as it is suspended by chain 123 until the positions of the work head assembly and crosstie kicker assembly have been reversed. The housing 24 is then lowered until it rests on the tracks and the vehicle is moved back toward the housing 24 and the housing is then reconnected to the vehicle.

As illustrated in FIG. 2, the work head assembly 32 is located at one end of the housing 24 while the crosstie kicker assembly 35 is located at the opposite end of the housing, which locates these elements on opposite sides of the railroad track. The work head assembly 32 is mounted on a main boom 130 which is slidably received in the upper portion of housing 24. A plurality of bearings are mounted on the main boom 130 and on the surfaces of housing 24 so as to allow the end portion of the main boom to move into and out of the housing. Hydraulic ram 132 is located in housing 24 beneath main boom 130, and the cylinder 133 of the ram 132 is connected to the housing by crosspin 134, and a ramrod 135 extends from the cylinder 133 toward the cross head assembly 32. Work head assembly support bracket 136 is rigidly connected to the protruding end of main boom 130, and the ramrod 135 is connected to the lower portion of the support bracket 136 and functions to move the support bracket 136 back and forth with respect to housing 24.

As illustrated in FIG. 4, work head housing 138 surrounds work head support bracket 136 and defines a side opening 139 that faces housing 24. The opening 139 in housing 138 is of a size sufficient to slide over the end of housing 24 so as to close the end of housing 24 when the work head assembly is retracted.

As illustrated in FIG. 2, the work head assembly 32 includes clamp assembly 140, shovel assembly 141, and crosstie push bar 142. The clamp assembly 140 is located adjacent the housing 24 and comprises clamp

arms 144 and 145 that are pivotally connected at their upper ends (not shown) to work head assembly housing 138, and hydraulic ram 146 functions to move the lower clamp jaws 148 of each clamp arm 144 and 145 toward and away from each other. Work head assembly housing 138 includes outwardly protruding flanges 149, and the clamp arms 144 and 145 are received between the flanges 149 so that the flanges tend to stabilize and guide the movements of the clamp arms.

Shovel assembly 141 is best illustrated in FIG. 3 and includes a support framework that has upwardly extending framework elements 151 and 152 that are located outside of work head assembly housing 138, crosshead 153 rigidly connected to the upper ends of elements 151 and 152, and shovel 154 rigidly connected to the lower ends of elements 151 and 152. Hydraulic rams 155 and 156 are located on opposite sides of the framework 150 and are each connected to the crosshead 153 and to the work head assembly housing 138. When the rams 155 and 156 are actuated, the rams lift or lower the entire framework 150 with respect to the work head housing 138, to lift or lower the spade 154. The spade 154 includes a support plate 158 and a plurality of downwardly protruding teeth 159.

Crosstie push bar 142 is telescopically mounted in work head assembly housing 138 at a position outboard from clamp assembly 140 and shovel assembly 141. Protrusion 161 is connected to the push bar 142 and extends through slot 162 in the housing, and the arrangement allows the push bar to reciprocate within the housing without falling out from the bottom of the housing.

Tilt ram 164 has its cylinder 165 connected to work head assembly support bracket 136 and its ramrod 166 connected to housing 138. When the ramrod 166 is distended or retracted, the entire workhead assembly housing 138, including clamp assembly 140, shovel assembly 141 and push bar 142 will tilt between a substantially upright attitude and a tilted attitude that corresponds to the end surface 24a of housing 24 and the adjacent surface 136a of the work head support bracket 136. Thus, the entire assembly is pivotable about pivot pin 135a to which the ramrod 135 of power ram 132 is connected.

As is illustrated in FIG. 5, hydraulic tank 170 maintains a supply of hydraulic fluid for the pump 14, and supply conduits 171 supply the fluid to the pump while the return conduits 172 return the fluid to the tank from the various operative systems throughout the vehicle. A plurality of solenoid valves 173, 174, 175, 176, 177, 178, 179, 180, 181, 182, 183 and 184 are supplied with liquid under pressure through conduits 185, 186, 187 and 188 from the pump 14. These solenoid valves control the various rams on the vehicle. For example, solenoid valve 173 is a two-position valve which alternately charges either conduit 190 or 191 with liquid to distend or retract double acting kicker ram 103 of crosstie kicker assembly 35. The liquid flowing away from kicker ram 103 comes back through one of the conduits 190 or 191 and flows back to the supply tank 170 through return conduits 172. Solenoid valves 174 and 175 function in a similar manner to charge conduits 192 and 193 and conduits 194 and 195 respectively, to control double acting main ram 132 that distends and retracts the work head assembly 132 from the housing 24, and to operate reversible travel motor M to move the vehicle along the tracks. The remaining solenoid and conduit arrangements are similar in that solenoid valve

196 controls conduit 196 to charge conduit 197 and conduit 198 to charge conduit 199, and solenoid valve 200 controls conduit 201 to charge conduit 202 and conduit 203 to charge conduit 204, and solenoid valve 205 controls conduit 206 to charge conduit 207 and conduit 208 to charge conduit 209, and solenoid valve 210 controls conduit 211 to charge conduit 212 and conduit 213 to charge conduit 214, and solenoid valve 215 controls conduit 216 to charge conduit 217 and conduit 218 to charge conduit 219, and solenoid valve 220 controls conduit 221 to charge conduit 222 and conduit 223 to charge conduit 224, and solenoid valve 225 controls conduit 226 to charge conduit 227 and conduit 228 to charge conduit 229, and solenoid valve 230 controls conduit 231 to charge conduit 232 and conduit 233 to charge conduit 234, and solenoid valve 235 controls conduit 236 to charge conduit 237 and conduit 238 to charge conduit 239, and solenoid valve 240 controls conduit 241 to charge conduit 242 and conduit 243 to charge conduit 244, and solenoid valve 245 controls conduit 246 to charge conduit 247 and conduit 248 to charge conduit 249, and solenoid valve 250 controls conduit 251 to charge conduit 252 and conduit 253 to charge conduit 254, and solenoid valve 255 controls conduit 256 to charge conduit 257 and conduit 258 to charge conduit 259, and solenoid valve 260 controls conduit 261 to charge conduit 262 and conduit 263 to charge conduit 264, and solenoid valve 265 controls conduit 266 to charge conduit 267 and conduit 268 to charge conduit 269, and solenoid valve 270 controls conduit 271 to charge conduit 272 and conduit 273 to charge conduit 274, and solenoid valve 275 controls conduit 276 to charge conduit 277 and conduit 278 to charge conduit 279, and solenoid valve 280 controls conduit 281 to charge conduit 282 and conduit 283 to charge conduit 284, and solenoid valve 285 controls conduit 286 to charge conduit 287 and conduit 288 to charge conduit 289, and solenoid valve 290 controls conduit 291 to charge conduit 292 and conduit 293 to charge conduit 294, and solenoid valve 295 controls conduit 296 to charge conduit 297 and conduit 298 to charge conduit 299, and solenoid valve 300 controls conduit 301 to charge conduit 302 and conduit 303 to charge conduit 304, and solenoid valve 305 controls conduit 306 to charge conduit 307 and conduit 308 to charge conduit 309, and solenoid valve 310 controls conduit 311 to charge conduit 312 and conduit 313 to charge conduit 314, and solenoid valve 315 controls conduit 316 to charge conduit 317 and conduit 318 to charge conduit 319, and solenoid valve 320 controls conduit 321 to charge conduit 322 and conduit 323 to charge conduit 324, and solenoid valve 325 controls conduit 326 to charge conduit 327 and conduit 328 to charge conduit 329, and solenoid valve 330 controls conduit 331 to charge conduit 332 and conduit 333 to charge conduit 334, and solenoid valve 335 controls conduit 336 to charge conduit 337 and conduit 338 to charge conduit 339, and solenoid valve 340 controls conduit 341 to charge conduit 342 and conduit 343 to charge conduit 344, and solenoid valve 345 controls conduit 346 to charge conduit 347 and conduit 348 to charge conduit 349, and solenoid valve 350 controls conduit 351 to charge conduit 352 and conduit 353 to charge conduit 354, and solenoid valve 355 controls conduit 356 to charge conduit 357 and conduit 358 to charge conduit 359, and solenoid valve 360 controls conduit 361 to charge conduit 362 and conduit 363 to charge conduit 364, and solenoid valve 365 controls conduit 366 to charge conduit 367 and conduit 368 to charge conduit 369, and solenoid valve 370 controls conduit 371 to charge conduit 372 and conduit 373 to charge conduit 374, and solenoid valve 375 controls conduit 376 to charge conduit 377 and conduit 378 to charge conduit 379, and solenoid valve 380 controls conduit 381 to charge conduit 382 and conduit 383 to charge conduit 384, and solenoid valve 385 controls conduit 386 to charge conduit 387 and conduit 388 to charge conduit 389, and solenoid valve 390 controls conduit 391 to charge conduit 392 and conduit 393 to charge conduit 394, and solenoid valve 395 controls conduit 396 to charge conduit 397 and conduit 398 to charge conduit 399, and solenoid valve 400 controls conduit 401 to charge conduit 402 and conduit 403 to charge conduit 404, and solenoid valve 405 controls conduit 406 to charge conduit 407 and conduit 408 to charge conduit 409, and solenoid valve 410 controls conduit 411 to charge conduit 412 and conduit 413 to charge conduit 414, and solenoid valve 415 controls conduit 416 to charge conduit 417 and conduit 418 to charge conduit 419, and solenoid valve 420 controls conduit 421 to charge conduit 422 and conduit 423 to charge conduit 424, and solenoid valve 425 controls conduit 426 to charge conduit 427 and conduit 428 to charge conduit 429, and solenoid valve 430 controls conduit 431 to charge conduit 432 and conduit 433 to charge conduit 434, and solenoid valve 435 controls conduit 436 to charge conduit 437 and conduit 438 to charge conduit 439, and solenoid valve 440 controls conduit 441 to charge conduit 442 and conduit 443 to charge conduit 444, and solenoid valve 445 controls conduit 446 to charge conduit 447 and conduit 448 to charge conduit 449, and solenoid valve 450 controls conduit 451 to charge conduit 452 and conduit 453 to charge conduit 454, and solenoid valve 455 controls conduit 456 to charge conduit 457 and conduit 458 to charge conduit 459, and solenoid valve 460 controls conduit 461 to charge conduit 462 and conduit 463 to charge conduit 464, and solenoid valve 465 controls conduit 466 to charge conduit 467 and conduit 468 to charge conduit 469, and solenoid valve 470 controls conduit 471 to charge conduit 472 and conduit 473 to charge conduit 474, and solenoid valve 475 controls conduit 476 to charge conduit 477 and conduit 478 to charge conduit 479, and solenoid valve 480 controls conduit 481 to charge conduit 482 and conduit 483 to charge conduit 484, and solenoid valve 485 controls conduit 486 to charge conduit 487 and conduit 488 to charge conduit 489, and solenoid valve 490 controls conduit 491 to charge conduit 492 and conduit 493 to charge conduit 494, and solenoid valve 495 controls conduit 496 to charge conduit 497 and conduit 498 to charge conduit 499, and solenoid valve 500 controls conduit 501 to charge conduit 502 and conduit 503 to charge conduit 504, and solenoid valve 505 controls conduit 506 to charge conduit 507 and conduit 508 to charge conduit 509, and solenoid valve 510 controls conduit 511 to charge conduit 512 and conduit 513 to charge conduit 514, and solenoid valve 515 controls conduit 516 to charge conduit 517 and conduit 518 to charge conduit 519, and solenoid valve 520 controls conduit 521 to charge conduit 522 and conduit 523 to charge conduit 524, and solenoid valve 525 controls conduit 526 to charge conduit 527 and conduit 528 to charge conduit 529, and solenoid valve 530 controls conduit 531 to charge conduit 532 and conduit 533 to charge conduit 534, and solenoid valve 535 controls conduit 536 to charge conduit 537 and conduit 538 to charge conduit 539, and solenoid valve 540 controls conduit 541 to charge conduit 542 and conduit 543 to charge conduit 544, and solenoid valve 545 controls conduit 546 to charge conduit 547 and conduit 548 to charge conduit 549, and solenoid valve 550 controls conduit 551 to charge conduit 552 and conduit 553 to charge conduit 554, and solenoid valve 555 controls conduit 556 to charge conduit 557 and conduit 558 to charge conduit 559, and solenoid valve 560 controls conduit 561 to charge conduit 562 and conduit 563 to charge conduit 564, and solenoid valve 565 controls conduit 566 to charge conduit 567 and conduit 568 to charge conduit 569, and solenoid valve 570 controls conduit 571 to charge conduit 572 and conduit 573 to charge conduit 574, and solenoid valve 575 controls conduit 576 to charge conduit 577 and conduit 578 to charge conduit 579, and solenoid valve 580 controls conduit 581 to charge conduit 582 and conduit 583 to charge conduit 584, and solenoid valve 585 controls conduit 586 to charge conduit 587 and conduit 588 to charge conduit 589, and solenoid valve 590 controls conduit 591 to charge conduit 592 and conduit 593 to charge conduit 594, and solenoid valve 595 controls conduit 596 to charge conduit 597 and conduit 598 to charge conduit 599, and solenoid valve 600 controls conduit 601 to charge conduit 602 and conduit 603 to charge conduit 604, and solenoid valve 605 controls conduit 606 to charge conduit 607 and conduit 608 to charge conduit 609, and solenoid valve 610 controls conduit 611 to charge conduit 612 and conduit 613 to charge conduit 614, and solenoid valve 615 controls conduit 616 to charge conduit 617 and conduit 618 to charge conduit 619, and solenoid valve 620 controls conduit 621 to charge conduit 622 and conduit 623 to charge conduit 624, and solenoid valve 625 controls conduit 626 to charge conduit 627 and conduit 628 to charge conduit 629, and solenoid valve 630 controls conduit 631 to charge conduit 632 and conduit 633 to charge conduit 634, and solenoid valve 635 controls conduit 636 to charge conduit 637 and conduit 638 to charge conduit 639, and solenoid valve 640 controls conduit 641 to charge conduit 642 and conduit 643 to charge conduit 644, and solenoid valve 645 controls conduit 646 to charge conduit 647 and conduit 648 to charge conduit 649, and solenoid valve 650 controls conduit 651 to charge conduit 652 and conduit 653 to charge conduit 654, and solenoid valve 655 controls conduit 656 to charge conduit 657 and conduit 658 to charge conduit 659, and solenoid valve 660 controls conduit 661 to charge conduit 662 and conduit 663 to charge conduit 664, and solenoid valve 665 controls conduit 666 to charge conduit 667 and conduit 668 to charge conduit 669, and solenoid valve 670 controls conduit 671 to charge conduit 672 and conduit 673 to charge conduit 674, and solenoid valve 675 controls conduit 676 to charge conduit 677 and conduit 678 to charge conduit 679, and solenoid valve 680 controls conduit 681 to charge conduit 682 and conduit 683 to charge conduit 684, and solenoid valve 685 controls conduit 686 to charge conduit 687 and conduit 688 to charge conduit 689, and solenoid valve 690 controls conduit 691 to charge conduit 692 and conduit 693 to charge conduit 694, and solenoid valve 695 controls conduit 696 to charge conduit 697 and conduit 698 to charge conduit 699, and solenoid valve 700 controls conduit 701 to charge conduit 702 and conduit 703 to charge conduit 704, and solenoid valve 705 controls conduit 706 to charge conduit 707 and conduit 708 to charge conduit 709, and solenoid valve 710 controls conduit 711 to charge conduit 712 and conduit 713 to charge conduit 714, and solenoid valve 715 controls conduit 716 to charge conduit 717 and conduit 718 to charge conduit 719, and solenoid valve 720 controls conduit 721 to charge conduit 722 and conduit 723 to charge conduit 724, and solenoid valve 725 controls conduit 726 to charge conduit 727 and conduit 728 to charge conduit 729, and solenoid valve 730 controls conduit 731 to charge conduit 732 and conduit 733 to charge conduit 734, and solenoid valve 735 controls conduit 736 to charge conduit 737 and conduit 738 to charge conduit 739, and solenoid valve 740 controls conduit 741 to charge conduit 742 and conduit 743 to charge conduit 744, and solenoid valve 745 controls conduit 746 to charge conduit 747 and conduit 748 to charge conduit 749, and solenoid valve 750 controls conduit 751 to charge conduit 752 and conduit 753 to charge conduit 754, and solenoid valve 755 controls conduit 756 to charge conduit 757 and conduit 758 to charge conduit 759, and solenoid valve 760 controls conduit 761 to charge conduit 762 and conduit 763 to charge conduit 764, and solenoid valve 765 controls conduit 766 to charge conduit 767 and conduit 768 to charge conduit 769, and solenoid valve 770 controls conduit 771 to charge conduit 772 and conduit 773 to charge conduit 774, and solenoid valve 775 controls conduit 776 to charge conduit 777 and conduit 778 to charge conduit 779, and solenoid valve 780 controls conduit 781 to charge conduit 782 and conduit 783 to charge conduit 784, and solenoid valve 785 controls conduit 786 to charge conduit 787 and conduit 788 to charge conduit 789, and solenoid valve 790 controls conduit 791 to charge conduit 792 and conduit 793 to charge conduit 794, and solenoid valve 795 controls conduit 796 to charge conduit 797 and conduit 798 to charge conduit 799, and solenoid valve 800 controls conduit 801 to charge conduit 802 and conduit 803 to charge conduit 804, and solenoid valve 805 controls conduit 806 to charge conduit 807 and conduit 808 to charge conduit 809, and solenoid valve 810 controls conduit 811 to charge conduit 812 and conduit 813 to charge conduit 814, and solenoid valve 815 controls conduit 816 to charge conduit 817 and conduit 818 to charge conduit 819, and solenoid valve 820 controls conduit 821 to charge conduit 822 and conduit 823 to charge conduit 824, and solenoid valve 825 controls conduit 826 to charge conduit 827 and conduit 828 to charge conduit 829, and solenoid valve 830 controls conduit 831 to charge conduit 832 and conduit 833 to charge conduit 834, and solenoid valve 835 controls conduit 836 to charge conduit 837 and conduit 838 to charge conduit 839, and solenoid valve 840 controls conduit 841 to charge conduit 842 and conduit 843 to charge conduit 844, and solenoid valve 845 controls conduit 846 to charge conduit 847 and conduit 848 to charge conduit 849, and solenoid valve 850 controls conduit 851 to charge conduit 852 and conduit 853 to charge conduit 854, and solenoid valve 855 controls conduit 856 to charge conduit 857 and conduit 858 to charge conduit 859, and solenoid valve 860 controls conduit 861 to charge conduit 862 and conduit 863 to charge conduit 864, and solenoid valve 865 controls conduit 866 to charge conduit 867 and conduit 868 to charge conduit 869, and solenoid valve 870 controls conduit 871 to charge conduit 872 and conduit 873 to charge conduit 874, and solenoid valve 875 controls conduit 876 to charge conduit 877 and conduit 878 to charge conduit 879, and solenoid valve 880 controls conduit 881 to charge conduit 882 and conduit 883 to charge conduit 884, and solenoid valve 885 controls conduit 886 to charge conduit 887 and conduit 888 to charge conduit 889, and solenoid valve 890 controls conduit 891 to charge conduit 892 and conduit 893 to charge conduit 894, and solenoid valve 895 controls conduit 896 to charge conduit 897 and conduit 898 to charge conduit 899, and solenoid valve 900 controls conduit 901 to charge conduit 902 and conduit 903 to charge conduit 904, and solenoid valve 905 controls conduit 906 to charge conduit 907 and conduit 908 to charge conduit 909, and solenoid valve 910 controls conduit 911 to charge conduit 912 and conduit 913 to charge conduit 914, and solenoid valve 915 controls conduit 916 to charge conduit 917 and conduit 918 to charge conduit 919, and solenoid valve 920 controls conduit 921 to charge conduit 922 and conduit 923 to charge conduit 924, and solenoid valve 925 controls conduit 926 to charge conduit 927 and conduit 928 to charge conduit 929, and solenoid valve 930 controls conduit 931 to charge conduit 932 and conduit 933 to charge conduit 934, and solenoid valve 935 controls conduit 936 to charge conduit 937 and conduit 938 to charge conduit 939, and solenoid valve 940 controls conduit 941 to charge conduit 942 and conduit 943 to charge conduit 944, and solenoid valve 945 controls conduit 946 to charge conduit 947 and conduit 948 to charge conduit 949, and solenoid valve 950 controls conduit 951 to charge conduit 952 and conduit 953 to charge conduit 954, and solenoid valve 955 controls conduit 956 to charge conduit 957 and conduit 958 to charge conduit 959, and solenoid valve 960 controls conduit 961 to charge conduit 962 and conduit 963 to charge conduit 964, and solenoid valve 965 controls conduit 966 to charge conduit 967 and conduit 968 to charge conduit 969, and solenoid valve 970 controls conduit 971 to charge conduit 972 and conduit 973 to charge conduit 974, and solenoid valve 975 controls conduit 976 to charge conduit 977 and conduit 978 to charge conduit 979, and solenoid valve 980 controls conduit 981 to charge conduit 982 and conduit 983 to charge conduit 984, and solenoid valve 985 controls conduit 986 to charge conduit 987 and conduit 988 to charge conduit 989, and solenoid valve 990 controls conduit 991 to charge conduit 992 and conduit 993 to charge conduit 994, and solenoid valve 995 controls conduit 996 to charge conduit 997 and conduit 998 to charge conduit 999, and solenoid valve 999 controls conduit 1000 to charge conduit 1001 and conduit 1002 to charge conduit 1003, and solenoid valve 1005 controls conduit 1006 to charge conduit 1007 and conduit 1008 to charge conduit 1009, and solenoid valve 1010 controls conduit 1011 to charge conduit 1012 and conduit 1013 to charge conduit 1014, and solenoid valve 1015 controls conduit 1016 to charge conduit 1017 and conduit 1018 to charge conduit 1019, and solenoid valve 1020 controls conduit 1021 to charge conduit 1022 and conduit 1023 to charge conduit 1024, and solenoid valve 1025 controls conduit 1026 to charge conduit 1027 and conduit 1028 to charge conduit 1029, and solenoid valve 1030 controls conduit 1031 to charge conduit 1032 and conduit 1033 to charge conduit 1034, and solenoid valve 1035 controls conduit 1036 to charge conduit 1037 and conduit 1038 to charge conduit 1039, and solenoid valve 1040 controls conduit 1041 to charge conduit 1042 and conduit 1043 to charge conduit 1044, and solenoid valve 1045 controls conduit 1046 to charge conduit 1047 and conduit 1048 to charge conduit 1049, and solenoid valve 1050 controls conduit 1051 to charge conduit 1052 and conduit 1053 to charge conduit 1054, and solenoid valve 1055 controls conduit 1056 to charge conduit 1057 and conduit 1058 to charge conduit 1059, and solenoid valve 1060 controls conduit 1061 to charge conduit 1062 and conduit 1063 to charge conduit 1064, and solenoid valve 1065 controls conduit 1066 to charge conduit 1067 and conduit 1068 to charge conduit 1069, and solenoid valve 1070 controls conduit 1071 to charge conduit 1072 and conduit 1073 to charge conduit 1074, and solenoid valve 1075 controls conduit 1076 to charge conduit 1077 and conduit 1078 to charge conduit 1079, and solenoid valve 1080 controls conduit 1081 to charge conduit 1082 and conduit 1083 to charge conduit 1084, and solenoid valve 1085 controls conduit 1086 to charge conduit 1087 and conduit 1088 to charge conduit 1089, and solenoid valve 1090 controls conduit 1091 to charge conduit 1092 and conduit 1093 to charge conduit 1094, and solenoid valve 1095 controls conduit 1096 to charge conduit 1097 and conduit 1098 to charge conduit 1099, and solenoid valve 1100 controls conduit 1099 to charge conduit 1100 and conduit 1101 to charge conduit 1102, and solenoid valve 1105 controls conduit 1106 to charge conduit 1107 and conduit 1108 to charge conduit 1109, and solenoid valve 1110 controls conduit 1111 to charge conduit 1112 and conduit 1113 to charge conduit 1114, and solenoid valve 1115 controls conduit 1116 to charge conduit 1117 and conduit 1118 to charge conduit 1119, and solenoid valve 1120 controls conduit 1121 to charge conduit 1122 and conduit 1123 to charge conduit 1124, and solenoid valve 1125 controls conduit 1126 to charge conduit 1127 and conduit 1128 to charge conduit 1129, and solenoid valve 1130 controls conduit 1131 to charge conduit 1132 and conduit 1133 to charge conduit 1134, and solenoid valve 1135 controls conduit 1136 to charge conduit 1137 and conduit 1138 to charge conduit 1139, and solenoid valve 1140 controls conduit 1141 to charge conduit 1142 and conduit 1143 to charge conduit 1144, and solenoid valve 1145 controls conduit 1146 to charge conduit 1147 and conduit 1148 to charge conduit 1149, and solenoid valve 1150 controls conduit 1151 to charge conduit 1152 and conduit 1153 to charge conduit 1154, and solenoid valve 1155 controls conduit 1156 to charge conduit 1157 and conduit 1158 to charge conduit 1159, and solenoid valve 1160 controls conduit 1161 to charge conduit 1162 and conduit 1163 to charge conduit 1164, and solenoid valve 1165 controls conduit 1166 to charge conduit 1167 and conduit 1168 to charge conduit 1169, and solenoid valve 1170 controls conduit 1171 to charge conduit 1172 and conduit 1173 to charge conduit 1174, and solenoid valve 1175 controls conduit 1176 to charge conduit 1177 and conduit 1178 to charge conduit 1179, and solenoid valve 1180 controls conduit 1181 to charge conduit 1182 and conduit 1183 to charge conduit 1184, and solenoid valve 1185 controls conduit 1186 to charge conduit 1187 and conduit 1188 to charge conduit 1189, and solenoid valve 1190 controls conduit 1191 to charge conduit 1192 and conduit 1193 to charge conduit 1194, and solenoid valve 1195 controls conduit 1196 to charge conduit 1197 and conduit 1198 to charge conduit 1199, and solenoid valve 1200 controls conduit 1201 to charge conduit 1202 and conduit 1203 to charge conduit 1204, and solenoid valve 1205 controls conduit 1206 to charge conduit 1207 and conduit 1208 to charge conduit 1209, and solenoid valve 1210 controls conduit 1211 to charge conduit 1212 and conduit 1213 to charge conduit 1214, and solenoid valve 1215 controls conduit 1216 to charge conduit 1217 and conduit 1218 to charge conduit 1219, and solenoid valve 1220 controls conduit 1221 to charge conduit 1222 and conduit 1223 to charge conduit 1224, and solenoid valve 1225 controls conduit 1226 to charge conduit 1227 and conduit 1228 to charge conduit 1229, and solenoid valve 1230 controls conduit 1231 to charge conduit 1232 and conduit 1233 to charge conduit 1234, and solenoid valve 1235 controls conduit 1236 to charge conduit 1237 and conduit 1238 to charge conduit 1239, and solenoid valve 1240 controls conduit 1241 to charge conduit 1242 and conduit 1243 to charge conduit 1244, and solenoid valve 1245 controls conduit 1246 to charge conduit 1247 and conduit 1248 to charge conduit 1249, and solenoid valve 1250 controls conduit 1251 to charge conduit 1252 and conduit 1253 to charge conduit 1254, and solenoid valve 1255 controls conduit 1256 to charge conduit 1257 and conduit 1258 to charge conduit 1259, and solenoid valve 1260 controls conduit 1261 to charge conduit 1262 and conduit 1263 to charge conduit 1264, and solenoid valve 1265 controls conduit 1266 to charge conduit 1267 and conduit 1268 to charge conduit 1269, and solenoid valve 1270 controls conduit 1271 to charge conduit 1272 and conduit 1273 to charge conduit 1274, and solenoid valve 1275 controls conduit 1276 to charge conduit 1277 and conduit 1278 to charge conduit 1279, and solenoid valve 1280 controls conduit 1281 to charge conduit 1282 and conduit 1283 to charge conduit 1284, and solenoid valve 1285 controls conduit 1286 to charge conduit 1287 and conduit 1288 to charge conduit 1289, and solenoid valve 1290 controls conduit 1291 to charge conduit 1292 and conduit 1293 to charge conduit 1294, and solenoid valve 1295 controls conduit 1296 to charge conduit 1297 and conduit 1298 to charge conduit 1299, and solenoid valve 1300 controls conduit 1299 to charge conduit 1300 and conduit 1301 to charge conduit 1302, and solenoid valve 1305 controls conduit 1306 to charge conduit 1307 and conduit 1308 to charge conduit 1309, and solenoid valve 1310 controls conduit 1311 to charge conduit 1312 and conduit 1313 to charge conduit 1314, and solenoid valve 1315 controls conduit 1316 to charge conduit 1317 and conduit 1318 to charge conduit 1319, and solenoid valve 1320 controls conduit 1321 to charge conduit 1322 and conduit 1323 to charge conduit 1324, and solenoid valve 1325 controls conduit 1326 to charge conduit 1327 and conduit 1328 to charge conduit 1329, and solenoid valve 1330 controls conduit 1331 to charge conduit 1332 and conduit 1333 to charge conduit 1334, and solenoid valve 1335 controls conduit 1336 to charge conduit 1337 and conduit 1338 to charge conduit 1339, and solenoid valve 1340 controls conduit 1341 to charge conduit 1342 and conduit 1343 to charge conduit 1344, and solenoid valve 1345 controls conduit 1346 to charge conduit 1347 and conduit 1348 to charge conduit 1349, and solenoid valve 1350 controls conduit 1351 to charge conduit 1352 and conduit 1353 to charge conduit 1354, and solenoid valve 1355 controls conduit 1356 to charge conduit 1357 and conduit 1358 to charge conduit 1359, and solenoid valve 1360 controls conduit 1361 to charge conduit 1362 and conduit 1363 to charge conduit 1364, and solenoid valve 1365 controls conduit 1366 to charge conduit 1367 and conduit 1368 to charge conduit 1369, and solenoid valve 1370 controls conduit 1371 to charge conduit 1372 and conduit 1373 to charge conduit 1374, and solenoid valve 1375 controls conduit 1376 to charge conduit 1377 and conduit 1378 to charge conduit 1379, and solenoid

176 controls the flow of pressurized liquid to conduits 196 and 197, solenoid valve 177 controls the flow of pressurized liquid to conduits 198 and 199 and solenoid valve 178 controls of pressurized fluid to conduits 200 and 201. With this arrangement, solenoid valve 176 controls the pair of double acting lift rams 29 that raise and lower the pairs of parallel support arms 21 and 22 that control the elevation of housing 24. Solenoid valve 177 controls the double acting rail clamp cylinders 61 on one side of the vehicle and the jack cylinder for the same side of the vehicle, and solenoid valve 178 functions like valve 175 in that it directs fluid to the travel motor M.

The solenoid valves 180, 181, 182, 183 and 184 at the top of FIG. 5 control the flow of pressurized liquid to conduits 202, 203, 204, 205, 206, 207, 208, 209, 210 and 211, 212, and 213. Solenoid valve 179 controls double acting clamp ram 146 which opens and closes the work head clamp, solenoid valve 180 controls double acting tilt ram 164 which tilts the work head assembly, solenoid valve 181 controls the double acting ram 68 of the turntable 66, solenoid valve 182 controls double acting shovel rams 155 and 156, the function of solenoid valve 183 is similar to that of solenoid valve 177 in that it controls the rail dogs and jack on the other side of the vehicle, and solenoid valve 184 functions like valves 175 and 178 to direct fluid to the travel motor M.

OPERATION

As illustrated in FIGS. 6-11, the vehicle 10 travels along the rails 215 and 216 of a railroad track 15. A supply of new crossties 217 are distributed on the rails 215 and 216 at locations adjacent where an old crosstie is to be removed from the railroad track. When the vehicle approaches a new crosstie 217, its push bars 94 (FIG. 1) engage the new crosstie and push the crosstie along the rails until the crosstie is located over an old crosstie that is to be removed from the track. The housing 24 is then lowered so that it tends to rest on the new crosstie. The wedge plates 92 and 93 (FIG. 1) will usually be located on opposite surfaces of the new crosstie, and the inclined surfaces 92a of the wedge plates 92 tend to push any other crossties ahead of the crosstie to be inserted further on down the track so as to form clearance between the crosstie under the housing 24 and any crosstie next ahead.

The rail dogs 55 are then lowered by disconnecting their chains 62 from the framework of the vehicle and are positioned with their jaws about the ball of rails 215 and 216. The operator then actuates solenoid valves 177 and 183 which pressurize their rail dog rams 61 and jack rams 49 to lift the forward portion of the vehicle and rails away from the bed of the railroad track.

The operator next actuates the solenoid valve 182 to move the shovel assembly 141 down into contact with the soil at the end of the old crosstie and solenoid valve 174 to reciprocate the work head in and out of its housing 24 as illustrated by arrow 218, whereupon the shovel 141 digs the ballast away from the end of the old crosstie and exposes the end of the old crosstie. When this function has been completed, the shovel 141 is retracted upwardly so that it is out of the way.

The operator then actuates solenoid valve 173 so as to move crosstie kicker assembly 35 in the direction indicated by arrow 219 (FIG. 8), which kicks or moves the new crosstie 217 to the left toward engagement with push bar 142. This accurately locates the new crosstie 217 so that the crosstie abuts the push bar 141 and is

located between the jaws of clamp assembly 140. The crosstie kicker is then retracted and as it approaches its fully-retracted position, its chains 111 and 112 pull the kicker feet 107 and 108 outwardly to their dashed line position (FIG. 1) where the kicker feet are now out of the way.

The operator then actuates solenoid valve 179 to move the clamp jaws together, whereupon the clamp solidly grasps the protruding end of the new crosstie 217, and then actuates solenoid valve 174 that distends the work head assembly and moves the new crosstie 217 further to the left as indicated by arrow 220, until the trailing end 217a of the new crosstie clears the exposed end 221a of the old crosstie 221. The housing 24 and therefore the work head assembly 32 are then lowered by actuating solenoid valve 176 until the trailing end 217a of the new crosstie 217 is at the level of the exposed end 221a of the old crosstie 221. Solenoid valve 174 is then reversed so as to move the work head, including clamp assembly 140 and push bar 142 in the direction indicated by arrow 222, which causes the new crosstie 217 to push against the exposed end of the old crosstie 221 and force the old crosstie out from beneath the rails 215 and 216. When the work head has been fully retracted, the new crosstie 217 will still protrude to some extent out to the side of the railroad track, but the clamping procedure on the end portion of the new crosstie can be repeated to grasp the new crosstie closer to its end portion and then thrust it further beneath its rails and into the space previously occupied by the old crosstie.

In some situations where an obstruction is present beside the railroad track, such as another track or an upwardly extending embankment, the new crosstie can be inserted by tilting the crosstie downwardly from the work head assembly toward abutment with the exposed end of the old crosstie so that the new crosstie clears the obstruction. In some situations it is desirable to reverse the positions of the crosstie kicker assembly with the work head assembly so that the work head assembly is free of obstructions and one of the cranes 70 can be used to lift the on-coming end of an old crosstie that is being replaced up over an obstruction.

In some situations it is desirable to remove old crossties without using the procedure of butting a new crosstie against the old crosstie. As illustrated in FIGS. 12 and 13, the crosstie kicker 35 is used to push against one end of the old crosstie to "break" the old crosstie from its position in the railroad bed, and the clamp assembly 140 grasps the protruding end of the crosstie and pulls it out from beneath the rails.

While this invention has been described in detail with particular reference to preferred embodiments thereof, it will be understood that variations and modifications can be effected within the spirit and scope of the invention as described hereinbefore and as defined in the appended claims.

I claim:

1. Apparatus for replacing crossties in a railroad track comprising:
a vehicle movable along the rails of a railroad track;
a support housing mounted on one end of said vehicle;
a crosstie kicker assembly supported by said support housing at one side of said vehicle;
a work head assembly movably supported by said support housing at the other side of said vehicle,
hydraulic power means connected between said

support housing and said work head assembly and arranged to apply approximately horizontal forces normal to the railroad track from said support housing to said work head assembly for moving said work head assembly in an approximately horizontal path toward and away from the railroad tracks,

hydraulic power means for tilting said work head assembly laterally with respect to the railroad tracks;

hydraulic power means for moving work head assembly vertically with respect to the railroad tracks; a crosstie clamp assembly attached to said work head assembly, said crosstie clamp assembly comprising a pair of opposed jaw elements arranged for relative spreading and gripping movement in a plane approximately parallel to the rails of the railroad track, and hydraulic power means for actuating said jaw elements,

a push bar supported by said work head assembly outboard of said crosstie clamp assembly and movable vertically with respect to said work head assembly to limit the movement of a crosstie between the opposed jaw elements of said crosstie clamp assembly;

a shovel means mounted to said work head assembly between said push bar and said crosstie clamp assembly, said shovel means being vertically movable to a level higher than said clamp assembly whereby said clamp assembly can be operated without interference from said shovel means and to a level lower than said clamp assembly whereby the shovel means reaches lower than the clamp means, and hydraulic power means for moving said shovel means vertically with respect to said work head assembly.

2. Apparatus for replacing crossties in a railroad track comprising a vehicle movable along a railroad track, a tool support housing at one end of said vehicle, tool means supported by said tool support housing at opposite sides of the railroad track, a parallel linkage connected between said vehicle and said tool support housing for guiding said tool support housing through up and down movements with respect to said vehicle, power means for raising and lowering said parallel linkage to raise and lower said tool support housing with respect to the railroad track, bar means supported by

and movable with said parallel linkage and including a support member at the end of the parallel linkage, said bar means being movable longitudinally with respect to said parallel linkage to project its support member away from said vehicle, and flexible connector means extending between said support member and said tool support housing whereby the tool support housing can be disconnected from the parallel linkage, the bar means distended with respect to the parallel linkage, the parallel linkage and bar means raised to lift the tool support housing with the flexible connector, and the tool support housing turned end-for-end.

3. Apparatus of claim 2 and further comprising a plurality of fluid conduits communicating between said vehicle and said tool support housing and a boom pivotally connected to said vehicle and extending from said vehicle above said tool support housing, whereby said boom supports said plurality of fluid conduits above said tool support housing and said tool support housing can turn end-for-end beneath said boom and said plurality of fluid conduits.

4. In an apparatus for replacing crossties in railroad tracks including a vehicle moveable along the rails of the railroad track and a support housing carried by said vehicle, the improvement therein of a work head assembly attached to said support housing and comprising:

a pair of opposed jaw elements arranged for relative spreading and gripping movement in a plane approximately parallel to the rails of the railroad track, and hydraulic power means for actuating said jaw elements,

a push bar support outboard of said opposed jaw elements and movable in an approximately vertical plane independently of said jaw elements to limit the movement of a crosstie between the opposed jaw elements of said crosstie clamp assembly;

a shovel means mounted between said push bar and said pair of opposed jaw elements, said shovel means being vertically movable alternatively from a level higher than said jaw elements whereby said jaw elements can be operated without interference from said shovel means to a level lower than said clamp assembly whereby the shovel means reaches lower than the clamp means, and hydraulic power means for moving said shovel means in an approximately vertical plane.
